CLAIM

The ornamental design for an automotive radar device as shown and described.

DESCRIPTION

FIG. 1 is a perspective view of an automotive radar device showing our new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top view thereof;

FIG. 7 is a bottom view thereof; and,

FIG. 8 is a perspective view of the automotive radar device viewed from another direction.

The broken line portion of the drawings is included to show unclaimed subject matter only and forms no part of the claimed design.

1 Claim, 8 Drawing Sheets(56)
